(57) **CLAIM**

The ornamental design for a sorting bin toy, as shown and described.

DESCRIPTION

The patent or application file contains at least one drawing executed in color. Copies of this patent or patent application publication with color drawing(s) will be provided by the Office upon request and payment of the necessary fee.

FIG. 1 is a bottom view the central bin component of my new design for a sorting bin toy;

FIG. 2 is a top view thereof;

FIG. 3 is a side view thereof;

FIG. 4 is a top perspective view thereof;

FIG. 5 is a bottom perspective view thereof;

FIG. 6 is a side view of the peripheral bin of the sorting bin toy;

FIG. 7 is a front view thereof;

FIG. 8 is a bottom side view thereof;

FIG. 9 is a bottom view thereof;

FIG. 10 is a top view thereof;

FIG. 11 is a side-top perspective view thereof;

FIG. 12 is a top perspective view thereof;

FIG. 13 is a to, rear and side perspective view thereof;

FIG. 14 is a rear and top perspective view thereof;

FIG. 15 is a top perspective view of a partially assembled sorting bin toy;

FIG. 16 is a top view of the fully assembled sorting bin toy;

FIG. 17 is a bottom view thereof;

FIG. 18 is a side view thereof;

FIG. 19 is a bottom perspective view of the sorting bin toy;

FIG. 20 is a top perspective view thereof; and,

FIG. 21 is a top and side perspective view thereof.
